Application February 12, 1943, Serial No. 475,625

8 Claims. (Cl. 134—59)

1

The present invention relates to improvements in the method and means of sterilizing tubular containers and more particularly to improvements in a washing machine capable of cleansing a variety of sizes and shapes of containers successively or simultaneously without danger of fracture and without undue loss or waste of the cleansing fluids during the washing process.

The present invention is an improvement on, and a continuation in part of, my prior application Serial No. 410,727, now Patent #2,379,789, dated July 3, 1945, and has for a primary aim to render available a machine organization capable of automatically feeding, sterilizing, and discharging delicate tubular containers such as, but not limited to, glass ampule and suture tubes, in an efficient manner.

Another aim of the invention is to improve and render available a sturdy yet flexible washing machine structure whose cleansing capacity in tubes per minute may be increased or decreased to suit a user's requirements, a machine that is thorough in its operation and economical to operate, a machine that, by making a few simple adjustments, may be adapted to receive and cleanse various sizes and shapes of glass containers, simultaneously, if the needs require, and a machine embodying a control means adapted for either continuous or cyclic operation.

A further aim of the invention is to eliminate the heretofore customary operation of hand feeding and the dangers incident thereto, such as glass splintering, and to further improve the character of the cleansing mechanisms and operations to the end that one is assured that tubes to be sterilized are not only untouched by human hands during the sterilization process but are also free of small splinters of glass or other foreign particles that might otherwise be contained or produced therein during the initial stages of manufacture.

The invention further undertakes to render the operation of cleaning more thorough than is possible by prior methods by subjecting each tube or container to a succession of different cleansing operations each of which may be followed by a liquid expelling and drying operation that removes all traces of the cleansing fluid used during the previous stage and thereby to condition the tubes to receive the same or a different cleansing fluid during a next following stage.

Still another objective of this invention is to conserve the cleansing fluid or fluids used during the washing operations. This objective is attained first by providing a plurality of separate

2

systems arranged to deliver independently of one another a selected cleaning fluid at a controllable rate at a given station to the interior of a tube only while the tube is at that station. During the transit of the tubes from station to station, the supply of cleaning fluid is closed off automatically. In cooperation with this method of supplying cleaning fluid intermittently, the fluid previously supplied to a given tube is separately collected and returned to its individual reservoir where it may be filtered or otherwise processed and re-used. In this way, cleaning fluids are used only when and in an amount necessary and there is no mixing of two or more cleaning fluids together which might render them less efficient or unusable for the purpose.

Another objective of the invention is to cooperatively associate with the foregoing an improved control system operable automatically to bring the cleansing machine to a stop at any time during the successive cleaning stages with the various elements and parts thereof in a position such that each of the several valves controlling the respective fluid supply systems is closed off, so that the machine may not inadvertently come to rest and be left idle with the fluid pressure systems still functioning.

Still another objective of the invention is to provide an improved means for carefully and accurately locating the tubes to be cleansed on each of the cleaning nozzles in a manner that eliminates the possibility of fracture or chipping heretofore occasioned in hand loading devices, and for definitely relating the loading mechanisms with the tube translating and with the valve control and stopping mechanisms so that not only will the machine remain properly timed but that, when stopped, the valves will be closed and the feeding and tube locating means will be in position to receive a new batch of tubes.

This invention further aims to render available a washing machine whose capacity and number of tube receiving needles and cleaning stages may be increased or decreased to suit particular needs without severe reconstruction or reorganization.

In attaining the aims of the invention it is proposed to arrange a conveyor structure with a series of transversely extending trough assemblies, each of which carries one or more radiating tubular needles on which the tubes to be cleaned are located. In the instant embodiment the trough assemblies are removably attached to the links of chains that pass over cog wheels intermittently revolvable on horizontal axes. As

the cogs are intermittently actuated, the troughs and needles pass from the under side of the wheel axis to a horizontal position where synchronously driven tube feeding mechanisms align the tubes and needles and place the tubes on the needles. The next movement of the conveyor lifts the tubes out of the loading mechanism, and subsequent movements place them in a vertical position, with their open ends down. Each trough assembly is formed with a laterally extending common conduit in communication with each of the needle jets, and whose outer end is adapted to be engaged successively by each of a series of independent fluid supply nozzles. The supply nozzles are normally stationary relative to the movement of the troughs, but have a reciprocating motion timed with the conveyor movements so that after each trough arrives at a station a connection is made with a separate fluid system and the particular cleaning fluid or agent of that system is forced through the supporting needles to the interior of the inverted tubes. In the present embodiment eight effective stations have been illustrated, and as one may desire to follow each injection of cleaning fluid with a drying medium, four of the stations might be termed cleaning stations and the intervening four, drying stations. The invention, however, comprehends various combinations and the foregoing example is but representative of the many combinations made possible by this invention.

The mechanisms are arranged, however, so that immediately upon the shutting off of the cleansing fluid at the first station of a pair, the inverted tubes drain into the troughs and may continue draining while the conveyor moves another step. At the next station, a connection with an air supply, for example, is made to hasten the expulsion and drying of the tube. Meanwhile, the liquid collecting in the troughs during the washing transferring and the expulsion stages, is free to flow into a catch basin and from there conducted back to the reservoir. Each pair of stations has its own catch basin so that, in the instant example, as many as four different cleaning agents may be used successively on each tube and the respective liquids separately collected for re-use.

Meanwhile, additional tubes are being fed and located on the needles at the loading station, by means driven by the conveyor driving means, and the thoroughly cleaned tubes are being discharged from the needles at the end station on to a conveyor or other mechanism leading to packaging or filling devices. The operation is such that the attendant merely places unclean tubes, which may be of like size or of different sizes, in the loading channels, after which they are automatically aligned with the washing needles, placed thereon, and moved through the successive cleansing, sterilizing and drying stations, and the sterile tubes thereafter discharged upon a conveyor or receiving means ready for the subsequent operations of filling and sealing. The washing operation is continuously intermittent and allows just enough dwell period at each station to insure proper loading, proper connecting and disconnecting of the fluid lines, and cyclic operation of the control valves, to insure adequate sterilization and drying time without waste or mixing of the ingredients. Following the initial operation of placing unclean tubes in the feeding racks, the machine operation is entirely automatic in its functioning.

Other objects and advantages will be in part indicated in the following description and in part

rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Figure 1 is a side view of a washing machine constructed in accordance with this invention.

Fig. 1A is a fragmentary view of a portion of the machine illustrated in Fig. 1 equipped with a modified form of loading mechanism.

Fig. 1B is a plan view of the loading mechanism illustrated in Fig. 1A.

Fig. 2 is an end view thereof, partly in section better to illustrate the drive means and the mechanisms for coordinating the movements of the several elements and controls.

Fig. 3 is a rear view of a portion of the machine illustrating the valves and part of the control system.

Fig. 4 is a diagrammatic illustration of one form of control circuit.

Fig. 5 is a plan view of the loading mechanism illustrated in Fig. 1.

Fig. 6 is an end view thereof; Fig. 7 is an enlarged view of a portion of the tube and needle aligning means; and Fig. 8 is a sectional view taken through one of the loading troughs and aligning means.

Referring more particularly to Figures 1 and 2, the washing machine illustrated is mounted upon a pair of leg standards 10, and comprises essentially, a pair of lower rails 11, 12 and a pair of upper rails 13, 14, between which a series of bearing plates 15, 16, 17, 18, are secured. The construction is such that by using increased or decreased lengths of rails 11-14, and adding or removing pairs of bearing plate units 15-18, the length of the machine may be altered and its capacity changed to suit specific requirements without expensive reconstruction or time consuming delays. This improved structure is set forth and claimed more specifically in my copending application Serial No. 514,930, Dec. 20, 1943.

The supporting rails 11-14 are spaced apart, as in Fig. 2, and the channel therebetween contains substantially all of the actuating mechanisms. The conveyor mechanism also travels between the supporting rails and includes two linked chain structures 19 and 20, whose pivot rolls 21 engage notches 22 in driving and driven pairs of star wheels 23 and 24. The wheels 23 and 24 are fixedly mounted to shafts 25 and 26, respectively, and these are journaled in bearing blocks 27 and 28 supported by the main frame. Between the pair of star wheels 23 a ratchet wheel 29 is fixed and adapted to be driven intermittently by means of a spring pressed pawl 30 mounted to the end of an actuating lever 31. The other end of the lever is pivoted to a cross support at 32 in such a position that a central portion of the lever overlies an actuating cam or roller 33 mounted upon a main cam shaft 34.

A motor 35 drives the main shaft through reduction gearing in a housing 36, and when operating the actuating arm 31 is caused to be raised and lowered once during each complete turn of the cam shaft. Each time the arm is lifted the pawl 30 engages a notch in the ratchet wheel and indexes the wheel one position. Such

movements, it will be seen, advances the conveyor step by step in a counterclockwise direction (in Fig. 1), leaving a dwell period between steps for loading and cleansing operations.

The links of the two conveyor chains are disposed directly opposite one another and are bridged by removable needle trough assemblies 40 each of which comprises an open ended trough member 41 having a plurality of aligned tube supporting hollow needles 42 radiating therefrom. Each needle is screw threaded to the bottom of a trough and its interior arranged to communicate with a common conduit 43 formed in the trough bottom. If it is desired to use less than six needles, the excess is removed and the holes appropriately capped. The conduit is closed at one end and its other end is provided with a conical seat 44 which is adapted to cooperate intermittently with the generally spherical end of fluid supply conduits 45.

In the present embodiment, eight supply stations and eight supply nozzles 45 have been illustrated. The number may, however, be increased or decreased as desired. Each of the nozzles 45 is normally spring pressed toward the seat 44 in a related trough assembly by a spring 46 operating between a loose collar 47 and a normally tight collar 48. By adjusting the tight collar to the left (in Fig. 2) the particular nozzle affected may be prevented from moving.

The several nozzles are actuated outwardly by means of levers 49 that are secured to an oscillatable shaft 50 journaled in brackets 51 secured to the framing. Another lever 52 is also secured to the shaft 50 and has its lower end pivotally connected to one arm of a bell crank lever 53 which in turn is pivoted at 54 in a bracket secured to the framing. The other end of the bell crank 53 carries a roller 55 that tracks on the periphery of a cam 56 secured to the cam shaft 34. Part of the surface of the cam 56 is relieved to provide a low portion into which the roller 55 drops during the movement of the conveyor. When the conveyor and the trough assemblies 40 have been indexed, the high portion of the cam 56 engages the roller 55 and actuates the bell crank clockwise from the position illustrated in Fig. 2. This movement through the toggle-like connection with lever 52 rocks the shaft 50 and levers 49 in a counterclockwise direction and the supply nozzles move inwardly and seat upon the respective seats in the trough assemblies.

After the nozzles are seated, a valve 60 associated with each supply line, is opened and fluid is directed through one or more of the lines 61, nozzles 45, and conduits 43 of the trough assemblies 40. Normally the valves 60 are closed, and are opened only when their respective valve stems 62 are depressed.

The means for opening the valves comprises a series of adjustable screws 63 carried at the free end of a pivoted bracket 64, each of which may be set so as to effect opening of its related valve to a greater or lesser extent depending upon requirements. The inner end of the bracket is pivoted to the framing, and carries an actuating arm member 65. The arm 65 mounts near its lower end, a roller 66 that engages a cam 67 mounted on the cam shaft. The cam 67 progresses from minimum to maximum diameter (see Fig. 4) so that the valves are gradually opened and quickly closed. The angular setting of the cam 67 on the cam shaft 34 is cooperatively related with the movements of the conveyor so that the opening and closing of the respective valves

is timed to occur during the period of dwell of the trough assemblies at the different stations, and between the interval of seating and unseating of the supply nozzles, to the end that no cleaning fluid flows to the needles until all connections are tight. The setting of the individual set screws 63 controls the volume of fluid supplied to the different groups of needles at the different stations.

10 The valve actuating arm 65 is guided near its lower end in a lug 68 at the side of the machine and the extreme lower end 69 projects therethrough to engage, during a certain portion of its travel, the plunger 70 of a sensitive switch 71. As diagrammatically illustrated in Fig. 4, the switch 71 is normally open and is connected to the drive motor in parallel with a manually operated normally open switch 72. When the operator actuates the switch 72 to a closed position, the motor 35 operates to drive the cam shaft 34 and the parts connected therewith, of which the valve actuating and switch control arm 65 is one. The cam shaft will make approximately one-quarter of a turn from the position shown in Fig. 4 (counterclockwise in Fig. 4) before the end 69 engages the plunger 70 and closes the switch 71. When this occurs the operator may release switch 72. Power operation continues until the cam roller 66 rides off the high part of the cam 67. At this point the valve actuating screws 63 are quickly lifted, allowing the valves to close, and the stem 69 lifts away from the switch plunger 70 and the switch 71 opens. The drive motor thereupon stops and the machine comes to rest with all valves closed; and with the loading mechanism retracted to a position ready to receive tubes. Spring elements 73, 74 and 75 assist in the reTRACTING movements of the several elements. The switch 71 is of conventional design having provision for overtravel of its actuating button, as for example, the yield spring represented in Fig. 4.

With this simplified form of control, the machine may be operated continuously, by maintaining the foot switch 72 closed, or cyclically by 45 the intermittent actuation of the foot switch. With either method of operation, however, the operation of the holding switch 71 is such as to insure that the fluid valves 60 are actuated to closed position by the time the main drive ceases 50 operation.

Cooperatively related with the indexing of the troughs is the operation of the loading mechanism illustrated more particularly in Figs. 1A, 1B, and a variant form in Figs. 1, 5-8. The function of the loading mechanism is to position the unclean ampules or tubes on the several needles of successive trough assemblies during the time they are at rest. Advantageously, a horizontal position of the needles, as illustrated in these figures, is selected as the loading station. The loading mechanism comprises a reciprocable carrier 80 that is guided on the rails 13 and 14 and actuated toward and away from the needles by mechanism driven from the common cam shaft 34. A cam element 81 having a gently rising side and a relatively steep side, is mounted upon the cam shaft 34 for that purpose and engages a roller 82 carried by a pivoted lever 83. The lower end of lever 83 connects with generally horizontal link member 84 which in turn connects with the lower end of a pivoted lever 85. The upper end of the lever 85 has a pin and slot engagement with the under side of the carrier 80, and as the main cam shaft rotates, the loading mechanism is reciprocated in timed relation with the conveyor 70 75

movements. A heavy spring 86 normally tends to urge the roller 82 against the cam 81 and the feed carrier 80 to retracted position.

As illustrated in the drawings, each trough assembly carries six needles whereby six ampules or tubes may be loaded and subsequently washed simultaneously. Likewise in the tube carrier 80 there are six channels 86 into which unclean tubes are to be laid. The forward portions of the channels 86 are somewhat tapered as at 87 and serve to guide the forward ends of the tubes into coaxial alignment with the needles. In the preferred form of loading mechanism shown in Figs. 1A and 1B the feeding and aligning of tube and needle is effected pneumatically during the forward travel of the carrier 80, whereas, in the form illustrated in Figs. 5, 6 and 8 the feeding and aligning is effected mechanically by the overtaking action of the individual plungers 88 which urge the respective tubes into the polished cone shaped recesses 89 provided in centering fingers 90. The centering fingers 90 move forward with the carrier 80 and are provided with similar cone cavities 91 in their sides facing the needles. Thus as the carrier advances, the several needles, should any be not perfectly straight, are guided by the cone walls 91 through a central opening 91a therein and into the ampule or tube that is centered in the cone on the other side.

With reference to the feeder illustrated in Figs. 5 and 6 each plunger 88 carries at its forward end a yielding abutment or pusher 92 that is compressed slightly when the rim of the tube or ampule has been advanced into the cone 89 as far as it will go.

When, however, the machine is equipped with pneumatic feeding means, a jet of air directed at the rear end of each ampule, urges the respective ampules forward along the channels and into the cones 89, without subjecting the ampules to physical contact with the ends of the feed plungers. Referring, particularly to Figs. 1A and 1B, the slide 80 carries a series of air jets 88a, one located in each of the channels 86, which receive compressed air from a common manifold 88b. The forward end of each air jet tube 88a is provided with a small opening 88c through which a stream of air is forced at the proper time and which moves the tube lying in the channel 86 therealong and into the cone 89. The air for the jets is controlled by a normally closed valve 88d secured to the frame, and which is opened automatically during the forward movement of the slide and closed again during the return movement.

To effect this operation, a pivoted valve actuating lever 88e is provided, the under side of which is formed with a cam surface 88f adapted to track upon a roller 88g of the slide. As the slide moves forward, the roller 88g rocks the lever about its pivot and depresses the valve stem, thus admitting the air to the manifold 88b and the jets 88a. When the pressure is on, the ampules immediately move forward into the cone chucks and are held by the streams of air pressure in positions ready to receive the needles. When the chucks open, the air streams continue to push the ampules forward well on the needles. Ahead of the control valve 88d a cut-off valve 88h may be installed for closing off or regulating the volume, and ahead of the valve 88d a pressure reducing or regulating valve (not shown) may be installed. The latter is desirable in installation

where the line pressure is too high. A jet pressure of approximately 5 pounds will advance medium size ampules efficiently. Larger and smaller tubes or heavier and lighter tubes will naturally require increased or decreased jet pressures. The air from the control valve is directed to the jets 88a through a line 88j and a flexible hose 88k, the latter type of connection providing for the movement of the jets relative to the fixed control valve.

The centering cone elements 89 and 91 are formed in two parts, each part being pivoted to the carrier at 93, some distance below the conical seats, and one leg 94 of each pair is pivoted to an actuating rod 95 and the other leg 96 of each pair, is pivoted to another actuating rod 97. A spring 98a connected to the ends of the rods 96 and 97 at the ends opposite their respective rollers is tensioned normally to hold all of the cones in closed position (full line position in Fig. 7). As the carrier travels forward, in response to the action of the cam 81, rollers 95a and 97a carried at the ends of the rods 95 and 97, engage stationary cams 98 and 99, and at the end of the forward movement, the incline of the stationary cams react to force the rods inwardly thereby effecting opening of the cones, i. e., to the position illustrated in dotted lines in Fig. 7. By the time this occurs the cleaning needles will have been centered and caused to project well into the ampule or tube necks and the succeeding indexing movement of the conveyor will effect a lifting of the ampules out of the channels 86 through the then opened centering cones. Just prior thereto, however, the opening of the centering cones permits the compressed air or the spring cushions 92 to push each tube forward further on the associated needle so that the ampules are well forward on the needles at the time indexing occurs, and consequently cannot fall off.

The means for advancing the plungers 88 relative to the carrier is illustrated in Figs. 1, 5, and 6 and comprises a sliding frame 100 that is guided on rods 101 that form part of the traveling carrier 80. The carrier also mounts at its rear portion, a pair of supporting rollers 102 rotatably mounted on a shaft 103. Each roller bears upon a track plate 104 secured to the main framing. The shaft 103 pivotally mounts a short lever 105 which has a pin and slot connection with the underside of the sliding frame 100, and by means of a rod-like extension 106, extends through an aperture 107 in a stationary crossplate member 108. Accordingly, as the carrier 80 moves forward, from the position illustrated in Fig. 1, the rod 106 fulcrums on the sides of the opening in the cross-plate and rocks the lever 105, and the movement of the lever 105 is transmitted to the slide 100 and plungers 88 secured thereto, whereby the latter move forward slightly faster than the forward movement of the carrier. This mechanism is not necessary when the pneumatic feed-er is employed.

The action of the various elements, on reverse movement of the carrier (to allow a succeeding needle group to move into loading position), is just the reverse to that explained, with the result that ampule space between the air jets or plungers and the centering cones is provided to permit easy insertion of unclean tubes into the channels.

In order that the loading mechanism be adapted for tubes of different length, each

plunger 88 is adjustable endwise relative to the slide 100. Set screws 108^a are provided to lock each plunger in adjusted position. The dotted lines in Fig. 5 illustrate the lower three plungers adjusted outwardly to accommodate slightly longer tubes. All plungers are, however, similarly adjustable and in consequence two or more sizes of tubes may be loaded and sterilized simultaneously. When necessary, one or more of the needles in the trough assemblies, may also be replaced by needles of a size best adapted to support the particular tubes to be sterilized. For exceptionally large tubes, the stationary cams 98 and 99 and the fulcrum plate 108 may be shifted rearwardly the requisite amount to allow correspondingly long needles to swing into position in front of the centering cones. With the machine equipped with the pneumatic feeder, all of the jets may be adjusted as a unit toward or away from the cone chucks, and if different length tubes are to be run simultaneously jet tubes of different lengths may be mounted in the slide and manifold.

As the needle assemblies move upwardly about the star wheel center 26, carrying and supporting thereon the ampules or tubes, the tubes should any be not fully down on the needles, are caused to settle thereon and are then carried along the top of the conveyor in an inverted position through the eight sterilizing stations. At the station *a*, hot water, for example, may be injected into the interior of the tubes through the needles and connections heretofore explained, and at the next station *a'*, air or other drying medium. At the third station *b*, another cleansing fluid, not necessarily water, may be injected followed by a drying or expelling medium at station *b'*, and similar cleansing and sterilizing operations performed at stations *c*, *c'*, *d*, and *d'*, thus insuring a high degree of sterility.

Although it is not essential, it has been found convenient to group the cleansing stations in pairs, as above mentioned, for the reason that the valves controlling the several fluid supply lines are opened after the trough assembly arrives in position, and closed before the assembly leaves that position and all the while liquid is draining from the inverted tubes into the troughs. This draining may continue during the transit from the first station of a pair to the second and in the interests of conserving and reclaiming, without mixing the different fluids, the fluid that drains from the ampules and trough while at the second station (of any pair) should be collected with the fluid that drains from the trough at the first station of the pair. This objective may be achieved by providing a plurality of catch basins 110 along the path of travel under the lips of the troughs. In the instant example four of such basins have been provided and each has an opening 111 therein which may be plugged, as illustrated, in Fig. 2, or piped to appropriate reclaiming apparatus or to reservoirs. Such liquid that may drip from the sides of the troughs during their travel about the conveyor is collected in an underlying pan 112 from which it escapes to a sump through a pipe 113.

As illustrated in Figs. 1 and 2, the ampules or tubes are prevented from being blown off the needles when the pressure is applied, by a vertically adjustable cover 114. This cover is open ended and normally is set to clear the bottoms of the inverted tubes without allowing the tubes too much end play therebetween.

At the completion of the several cleaning cycles the sterile tubes are carried from under the cover 114 and removed or discharged from the needles. In the embodiment illustrated herein an adjustable guide plate or chute 115 is provided on which the tubes are laid as the needles reach a position below the horizontal. When this occurs the sterile tubes automatically slide off the needles on to the chute and thence on to a conveyor belt 116. The link connection 117 and pin and recesses 118 afford means for adjusting the chute to different tube sizes.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:

1. In an ampule washing machine an indexable element, a series of ampule supporting and washing needles mounted on said element, means for indexing said washing needles successively from an ampule feeding station to a washing station and back to said feeding station, valve means and conduits for supplying cleansing fluid to the ampules while at the washing station, and means mechanically synchronized with said indexing means for actuating said valve means temporarily to an open position when the said needles are at the washing station, means for starting the machine in operation, and additional control means connected with and operated by said valve actuating means operative normally to stop the operating cycle of the machine upon the movement of said valve actuating means to a position closing said valve means.

2. An ampule sterilizing machine combining a series of intermittently movable ampule supporting assemblies, each having a fluid conduit therein adapted to be coupled intermittently with a source of supply fluid, a series of movable but normally stationary cleansing fluid supply lines, normally closed valve means in each of said lines for controlling the respective flows of cleansing fluids to the respective assemblies; means for moving said assemblies from one station to another and thereafter to couple said supply lines with the respective conduits in the respective assemblies and for actuating said valve means temporarily to an open position during the period of rest of said assemblies, means manually operable to start the operation of the machine, and additional means connected with said valve actuating means normally effective to continue the machine in operation and to stop same automatically upon the movement of said valve actuating means to a position closing said valves.

3. In an ampule washing machine, the combination of a conveyor, a series of members attached to said conveyor, a plurality of elongated ampule supporting jet elements extending from said members, each of said jet elements of each member having a central bore in communication with a transversely extending conduit formed in the member, a series of rectilinearly movable

fluid supply conduits, normally closed valve means in each of said supply conduits, means normally operative to bring said series of supply conduits into fluid tight relation with the conduits in said members and cyclically to open said valve means therein, and means associated with each of said valve opening means to control the flow opening of the valve means and thereby the fluid delivered to a related member and jet elements independently of the flow of fluid delivered through other valve means and supply conduits to their related members and jet elements.

4. In a device of the character described, a series of units, each of said units comprising an open ended trough shaped element mounting a plurality of tubular needles and having an open ended fluid conduit therein with which each of said tubular needles communicates, means for imparting an intermittent movement to said units, means operative when said units are at rest to connect the said fluid conduit of selected ones of said units with independent sources of fluid under pressure, and means adjacent the open ends of said trough shaped elements for separately collecting the fluid discharged through said needles.

5. In a device of the character described, a series of units, each of said units comprising a trough shaped element mounting a plurality of tubular needles and having an open ended fluid conduit formed therein with which each of said tubular needles communicates, means underlying said troughs for advancing said troughs intermittently, a series of supply conduits each having end portions disposed in the plane of movement of the troughs and in alignment with the open end of the fluid conduits thereof when the troughs are at rest, a control valve in each of said supply conduits, and control means for the valves including means synchronized with the trough advancing means for effecting actuation of selected ones of said valves, the fluid discharged through the effective valves, trough conduits, and needles, and collecting in the respective troughs being carried across the trough advancing mechanism to a point of discharge.

6. In a device of the character described, a container carrier comprising an elongated trough shaped element open at one end and mounting a plurality of tubular supports on which containers to be washed are adapted to be carried, said element having a lengthwise extending fluid conduit formed therein with which each of said tubular supports communicates for supplying fluid through the respective supports to the interior

of the containers, said conduit being closed at one end and open at its other end, and means for moving said element.

7. The combination set forth in claim 6 characterized by relatively movable means operable in timed relation with the movement of said element for establishing a connection with one end of the common fluid conduit in said element and a source of supply fluid.

8. In an ampule washing machine, an indexable element, a series of ampule supporting and washing needles mounted on said element, power means for indexing said element from an ampule feeding station to a washing station and back to said feeding station, conduit means at said washing station including normally closed valve means for supplying cleaning fluid to the washing needles while at that station, power means synchronized with said indexing means for effecting actuation of said valve means to open position during the period said element is at the washing station, means normally effective for initiating the indexing cycle, and additional means actuated by and controlled by said valve actuating means to continue the indexing cycle effective through one complete cycle of valve operation independently of said initiating means.

FRANK J. COZZOLI.
